UNITED STATES PATENT OFFICE.

HARVEY J. YAGER, OF SEATTLE, WASHINGTON.

ELECTRICALLY-OPERATED RAILWAY CROSSING AND SIGNAL.

1,312,377.

Specification of Letters Patent.

Patented Aug. 5, 1919.

Application filed February 21, 1918. Serial No. 218,554.

To all whom it may concern:

Be it known that I, HARVEY J. YAGER, a citizen of the United States, residing at Seattle, in the county of King and State of Washington, have invented certain new and useful Improvements in Electrically-Operated Railway Crossings and Signals; and I do hereby declare the following to be a full, clear, and exact description of the invention, such as will enable others skilled in the art to which it appertains to make and use the same.

This invention relates to improvements in electrically operated railway crossings and signals and has for one of its objects the provision of a device of this character, whereby the frogs of the crossing may be electrically actuated, so that they will be properly positioned for one track and then the other, and simultaneously illuminating signaling lights along the track to indicate which track of the crossing is open for a train or car to cross or proceed.

Another object of this invention is the provision of means located adjacent the crossing whereby the operation of the frogs and signal lights may be readily controlled and which signal lights are automatically controlled by the frogs moving into their different positions.

A further object of this invention is the provision of an electrically operated railway crossing and signal of the above stated character, which shall be simple, durable and efficient, and which may be manufactured and sold at a comparatively low cost.

With these and other objects in view, as will become more apparent as the description proceeds, the invention consists in certain novel features of construction, combination, and arrangement of parts as will be hereinafter more fully described and claimed.

For a complete understanding of my invention, reference is to be had to the following description and accompanying drawings, in which:

Figure 1 is a plan view of a railway crossing and signal.

Fig. 2 is a diagrammatical view illustrating the wiring diagram of the electrical

means for actuating the frogs and for illuminating and controlling the signal lights, and

Fig. 3 is a sectional view illustrating the electrical means for actuating the locking means to the arm.

Referring in detail to the drawings, the numeral 1 indicates as an entirety a railway crossing consisting of the track A and the track B. At the intersection of the tracks A and B, are positioned oscillatory frog members which have grooves 3 adapted to be alined with the grooves of the tracks so as to form a continuous track at the crossing, thereby obviating the jars and jolts now frequent to cars or trains when passing over crossings of the ordinary type. The grooves 3 have secured to their lower ends segments 4, which segments mesh with segments 5 carried by arms 6 and 7. The arms 6 and 7 are pivotally mounted as illustrated at 8 for oscillatory movement and are connected to each other in any well known manner whereby upon movement of one arm, a similar movement will be transmitted to the other arm. The pivotal point of the arm is upon a suitable supporting structure 9, and which supporting structure underlies the arm 7. The arm 7 is the operating arm for all of the frogs and has secured thereto electromagnets 10 and 11 upon opposite sides of the pivot 8 as clearly illustrated in the drawings. The electromagnet 10 has a winding a and the electrical current is adapted to extend through this winding in the direction indicated by the arrows to establish a south pole in the direction of one free end of the arm 7 and a north pole in the direction of the pivot 8. The electromagnet 11 is provided with a winding b and the electrical current passes through this winding b in the direction indicated by the arrows so as to establish a north pole adjacent the pivot 8 and a south pole in the direction of the other free end of the arm 7.

The magnets 10 and 11 are secured to the arm 7 by fasteners 12. A pair of electromagnets 13 and 14 are secured to the supporting structure 9 adjacent the electromagnet 10 and are arranged in the arc of a circle as clearly shown in the drawings. A similar

pair of electromagnets 15 and 16 are carried by the supporting structure 9 adjacent the electromagnet 11 and are also arranged in the arc of a circle. The electromagnet 13 5 is provided with windings *c* and *e* which windings extend in opposite directions and the electromagnet 14 is provided with oppositely extending windings *c* and *e*. The electromagnet 15 is provided with oppositely extending windings *c* and *e* and also the electromagnet 16. The pairs of electromagnets being provided with double windings and which windings extend in opposite directions of each other for the purpose of reversing 10 the poles of the magnets during the 15 operation of the frogs.

Located adjacent the crossing 1 is an observation tower or building 17 in which is positioned a double pivoted knife, switch 18. 20 Feed wires 19 and 20 lead into the tower 17. Contacts 21, 22, 23 and 24 are located in pairs upon one side of the pivot point of the switch 18 while contacts 25, 26, 27, and 28 are located in pairs upon the other side of 25 the switch 18. The contact 28 has the feed wire 20 connected thereto while the contact 22 has the feed wire 19 connected thereto. A conductor 29 is connected to the feed wire 20 and to the contact 23. A conductor 30 is 30 connected to the feed wire 19 and to the contact 25. Double knife switch 31 and 32 are located adjacent the knife switch 18 which is the main controlling switch. The switch 31 has associated therewith contacts 33 and 34, respectively, while the switch 32 has associated therewith contacts 36 and 37. The contacts 21 and 33 are connected by a conductor 38 while the contacts 34 and 24 are connected by a conductor 39. The contacts 26 and 36 are connected by a conductor 40, while the contacts 27 and 37 are connected by a conductor 41.

A pair of magnets 42 and 43 are carried by the supporting structure 9 adjacent the 45 electromagnets 15 and 16. A frame 44 is carried by the supporting structure 9 and overlies the electro-magnets 42 and 43 and has slidably mounted therein spring actuated catches 45, each provided with an armature 46 adapted to be attracted by the magnets 42 and 43 so as to move the catches 45 against the tension of the spring. The catches 45 are adapted to engage in notches 47 in the under face of the arm 7 for holding 50 the frogs 2 against accidental movement when in either of their operative positions or with the grooves 3 thereof in alignment with the grooves of the tracks A and B. A conductor 48 is connected to one sleeve of the switch 31 and to the magnet 42. A conductor 49 is connected to the magnet 42 and to one end of the winding *c* of the magnet 15. The other end of the winding *c* of the magnet 15 has connected thereto a conductor 50 which is connected to one end of the

winding *c* of the electro-magnet 16. A conductor 51 is connected to the other end of the winding *c* of the electro-magnet 16 and to the end of the winding *b* of the electro-magnet 11. It will therefore be noticed that 70 the electric current passing through the winding *c* in the direction indicated by the arrows of the magnet 15, a north pole will be established at the end of said magnet adjacent the magnet 11 and south pole established at the end of the magnet 16 adjacent the magnet 11, whereby the magnet 11 will be attracted by the magnet 15 and be repelled by the magnet 16. The conductor 52 is connected to the other end of winding *b* 80 of the magnet 11 and to one end of the winding *a* of the magnet 10. A conductor 53 is connected to the other end of the winding *a* of the electro-magnet 10 and to one end of the winding *e* of the electro-magnet 13. A conductor 54 is connected to the other end of the winding *e* of the electro-magnet 13 and to one end of the winding *e* of the electro-magnet 14. A conductor 55 is connected to the other end of the winding 90 *e* of the electro-magnet 14 and to the other sleeve of the switch 31, whereby upon having the switch 31 in engagement with the contacts 33 and 34 and the switch 18 in engagement with the contacts 21 and 24, the 95 frogs 2 will be rotated into a position as illustrated in Fig. 1 so that the grooves 3 thereof align with the grooves of the track A. As soon as the magnet 42 is energized, its respective latch 45 is disengaged from 100 the arm 7 for permitting the same to move into a position as illustrated in Fig. 1. By having the electric current pass through the windings of the electro-magnets 13 and 14 in the heretofore described manner establishes a south pole at the end of the magnet 13 adjacent the magnet 10 and a north pole at the end of the magnet 14 adjacent the magnet 10, whereby the electro-magnet 13 105 will attract the magnet 10 and the electro-magnet 14 will repel the electro-magnet 10 and which means co-operates with the heretofore described magnets in moving the arm 7. A conductor 56 is connected to one blade of the switch 32 and to the electro-magnet 110 43. A conductor 57 is connected to the electro-magnet 43 and to the winding *e* of the electro-magnet 15. A conductor 58 is connected to the other end of the winding *e* of the electro-magnet 15 and to one end of 115 the winding *e* of the electro-magnet 16. A conductor 59 is connected to the other end of the winding *e* of the electro-magnet 16 and to the conductor 51. A conductor 60 is connected to the conductor 53 and to one 120 end of the winding *c* of the electro-magnet 13. A conductor 61 is connected to the other end of the winding *c* of the electro-magnet 13 and to one end of the winding *c* of the 125 electro-magnet 14. A conductor 62 is con- 130

nected to the other end of the winding *c* of the electro-magnet 14 and to the other blade of the switch 32, whereby upon moving the switch 18 into engagement with the contacts 25, 26, 27 and 28 and having the switch 32 in a closed position, the arm 7 will be moved in the opposite direction from the heretofore described direction, positioning the frogs 2 so that the grooves 3 thereof will 10 aline with the grooves of the rails of the track B.

Contacts 64 and 65 are located upon each side of the arm 7 and each constitutes a spring arm 66. The spring arms 66 are 15 normally spaced from contacts 67 and 68. The spring arms 66 are adapted to be engaged by the arm 7 to be moved into engagement with their respective contacts 67 and 68 when the arm 7 is oscillated upon 20 its pivot 8. A conductor 69 is connected to the conductor 38 and to the contact 64. Electric lamps 70 and 71 are located upon the track B upon one side of the crossing 1 and the electric light 70 is preferably 25 white, while the electric light 71 is red. The red and white electric lights 72 and 73 are located upon the track B upon the opposite side of the crossing 1. Red and white electric lights 74 and 75 are located along side 30 of the track A on one side of the crossing 1 and red and white electric lights 76 and 77 are located along the same track but on the opposite side of the crossing. Red and white electric lights 78 and 79 are located in 35 the tower 17 and also red and white electric lights 80 and 81. A conductor 82 is connected to the contact 67 and to the electric lamp 71. A conductor 83 is connected to the electric lamp 71 and to the electric lamp 40 72. A conductor 84 is connected to the electric lamp 72 and to the electric lamp 75. A conductor 85 is connected to the electric lamp 75 and to the electric lamp 77. A conductor 86 is connected to the electric lamp 77 and to the electric lamp 78 located 45 in the tower 17. A conductor 87 is connected to the electric lamp 78 and to the electric lamp 79 which is located adjacent the electric lamp 78. A conductor 88 is connected to the electric lamp 79 and to the conductor 39, whereby a red light will be 50 displayed on track B indicating that the frogs are set in such a manner that the track A is open so that a train or car may proceed from the track A across the crossing. It will also be noted that the white 55 lights are illuminated on the track A indicating that the crossing or the frogs thereof are in a proper position for the train or car thereon to proceed. These lights are automatically illuminated when the frogs move into position as shown in Fig. 1 and by the controlling switch 18 being swung into engagement with the contacts 21, 22, 23 60 and 24 respectively. A conductor 89 is con- 65

nected to the conductor 40 and to the contact 65. A conductor 90 is connected to the contact 68 and to the electric lamp 70. A conductor 91 is connected to the electric lamp 70 and to the electric lamp 73. A conductor 70 92 is connected to the electric light 73 and to the electric light 74. A conductor 93 is connected to the electric light 74 and to the electric light 76. A conductor 94 is connected to the electric light 76 and to the 75 electric light 80, located in the tower 17. A conductor 95 is connected to the electric light 80 and to the electric light 81 located adjacent thereto. A conductor 96 is connected to the electric light 81 and to the 80 conductor 41, whereby upon moving the switch 18 into engagement with the contacts 25, 26, 27 and 28 respectively, to move the frogs so that the grooves thereof register with track B, white lights will be illuminated on track B while red lights are illuminated on track A. 85

While I have shown and described the preferred embodiment of my invention, it will be understood that minor 90 changes in construction, combination and arrangement of parts may be made without departing from the spirit and scope of the invention as claimed.

Having thus described my invention, what 95 I claim is:

1. In combination with a railway crossing including oscillatory frogs, and an actuating arm therefor, signal lights of different characters located about the crossing, an 100 electro-magnet carried by the arm, stationary electro-magnets located adjacent said magnet adapted to alternately repel and attract the first named magnet, and means energizing said magnet and illuminating 105 certain signal lights.

2. In combination with a railway crossing including oscillatory frogs, and an actuating arm therefor, signal lights of different characters located adjacent the crossing, an electro-magnet carried by the arm, stationary electro-magnets located adjacent said magnets and each having oppositely wound windings, and means energizing the windings of the magnets to oscillate the arm 110 115 and illuminate the signal lights.

3. In combination with a railway crossing including oscillatory frogs, and an actuating arm therefor, signal lights of different characters located adjacent the crossing, an electro-magnet carried by the arm and having a single winding, stationary electro-magnets located adjacent said magnet and having double windings and said windings extending in opposite directions, 120 125 an electrical means introducing electrical currents into the windings for oscillating the arm and illuminating the signal lights.

4. In combination with a railway crossing including oscillatory frogs, and an ac- 130

tuating arm therefor having catches, electro-magnets adapted to actuate said catches, and electro-magnet carried by said arm, stationary electro-magnets located adjacent the second named electro-magnets and having double windings extending in opposite directions, and means introducing electrical current into windings of the magnets so as

to oscillate the arm and illuminate the signal lights.

In testimony whereof I affix my signature in presence of two witnesses.

HARVEY J. YAGER.
